DESIGN FOR A CASING FOR TELEPHONE UNITS

William J. Muldoon, Hempstead, N. Y., assignor
to Control Instrument Company, Inc., Brooklyn, N. Y., a corporation of New York

Application August 21, 1944, Serial No. 114,960

Term of patent 14 years

(Cl. D26—14)

To all whom it may concern:

Be it known that I, William J. Muldoon, a citizen of the United States residing in Hempstead, in the county of Nassau and State of New York, have invented a new, original, and ornamental Design for a Casing for Telephone Units, of which the following is a specification, reference being had to the accompanying drawing, forming part thereof.

In the drawing:

Fig. 1 is a plan view of a casing for telephone units showing my new design.

Fig. 2 is a side elevation thereof, and

Fig. 3 is a plan view showing the interior of the casing.

What is claimed is:

The ornamental design for a casing for telephone units, as shown.

WILLIAM J. MULDOON.
